UNITED STATES PATENT OFFICE.

WILLIAM F. LEVISON, OF CLEVELAND, OHIO.

AUTOMOBILE LOCK.

Application filed February 11, 1924. Serial No. 692,009.

To all whom it may concern:

Be it known that I, WILLIAM F. LEVISON, a citizen of the United States, residing at Cleveland, in the county of Cuyahoga and State of Ohio, have invented certain new and useful Improvements in Automobile Locks, of which the following is a specification.

This invention relates to improvements in automobile locks having for an object to provide a simple and efficient means to prevent flow of fuel to the power plant of the automobile.

Another object is to provide a double locking means whereby to prevent manipulation of a fuel control valve by unauthorized persons.

Other objects will be in part obvious and in part pointed out hereinafter.

In order that the invention and its mode of operation may be readily understood by persons skilled in the art, I have in the accompanying illustrative drawings and in the following detailed description based thereon set out one possible embodiment of the same.

In these drawings:

Fig. 1. is a side elevation showing my improved locking device in use;

Fig. 2. is a top plan view thereof;

Fig. 3. is a horizontal section taken on a plane slightly below the center;

Fig. 4. is a sectional view taken substantially on the plane of 4—4 of Figure 5; and

Fig. 5. is a view showing the position of parts prior to assembly.

Having more particular reference to the drawing throughout which similar characters of reference designate similar parts this improved automobile lock may be broadly stated as comprising the positioning of a control valve in the fuel line preferably adjacent the carburetor and arranging thereover a two-part shell or casing which is securely locked in place in such a manner as to prevent unauthorized operation of the valve.

While other designs of valves may be employed, I preferably use a three-way type, two branches of which are arranged to connect in a straight line the fuel supply pipe 6 and the carburetor connection 7 while the third branch is open and extends laterally away from the engine body and carburetor as is obvious.

This third branch is arranged to permit

of connection thereto an air pipe or air pump by means of which the carburetor or the fuel line 6 to the supply tank may be readily cleaned, simultaneously or individually.

The rotatable valve 8 as shown is preferably provided with an operating finger piece or key 9 at each end, the function and advantage of which will be hereinafter apparent.

In order to prevent persons without authority from operating the valve and stealing the automobile, I provide a two-part shell or casing 10 which as shown, consists of identically formed shell halves, each being in the form of a cylinder 11 having a closed outer end 12 and an open inner end 13. The closed end 12 of each half is provided with an opening or key slot 14 so that upon assembly as in Figures 1 and 2, the finger-pieces or keys 9 will each snugly fit in a slot, thereby preventing turning of the valve if by any chance a person should break away the central portion of either end of the shell. It is obvious that the key being fitted in a slot at the other end it is still impossible to operate the valve. The meeting faces of the two halves are provided with recesses or depressions 15 which permit the parts to straddle the branches of the valve coupling and entirely enclose the body portion.

Each half of the casing is provided with a pair of diametrically oppositely disposed legs 16 which are slightly longer than the cylinder body. A pair of aligned openings 17 is formed in the legs to permit the insertion of the shackle 18 of a lock 19 as shown in Figures 1 and 2. The inner ends 20 of the legs 16 are continued to the bottom or closed end of the cylinder forming ribs 20 which snugly fit in between the branches of the coupling and against the valve body, thus preventing turning of the shell when in locked position. It is understood that the cylinders and legs are integrally formed as by casting in a unit. Obviously the pair of legs on one cylinder are arranged at right angles to the other pair and formed in the cylinder ends at points near the wall midway between the legs are openings 21 in which the legs fit.

Upon turning the valve to the position shown in Figure 3, the fuel supply is cut off and the housing or shell halves are placed around the valve body, the keys or

finger pieces 9 being projected slightly through the slots 14 in the cylinder ends or if preferred may be entirely covered by the shell through elimination of the slots. In 5 this position the ends of the legs 16 project through the ends of the cylinders thereby permitting insertion of the lock shackles into the openings in the legs.

This completes the locking operation and 10 the parts are now positioned so that both locks or shell halves must be broken before the control valve can be operated.

Manifestly certain minor changes in the structural details may be resorted to and 15 such of these changes as fall within the scope of the appended claims, I consider within the spirit of my invention.

I claim:

1. In an automobile lock, the combination 20 of a valve arranged in the fuel supply line, a two-part housing for the valve, a pair of legs carried by each part of the housing, each part having openings, and said legs being adapted to be received in the openings and means to lock the legs in said openings.

2. In an automobile lock, the combination 30 of a valve arranged in the fuel supply line, a finger piece carried by the valve, a two-part interlockable housing adapted to enclose the valve, and said housing having a slot to snugly receive the finger piece to prevent relative movement therebetween.

3. In an automobile lock, the combination 35 of a valve arranged in the fuel supply line, a pair of operating finger pieces carried by the valve, a two-part interlockable housing for the valve, and connection between the housing and finger pieces to prevent relative shifting of position.

4. In an automobile lock, the combination 45 of a valve arranged in the fuel supply line, a two-part housing for the valve, each part having a pair of diametrically opposed parallel legs, said pairs of legs being relatively at right angles, each part of the housing having spaced openings to receive the legs of the other part and means for locking the legs in the openings.

5. In an automobile lock, the combination 50 of a valve arranged in the fuel supply line, a two-part housing for the valve, each part having a pair of diametrically opposed parallel legs, said pairs of legs being relatively at right angles, each part of the 55 housing having spaced openings to receive the legs of the other part, and shoulders arranged upon the inner face of each housing part as extensions of said legs, and adapted to snugly fit against the valve body 60 and means for locking the legs in the openings.

6. In an automobile lock, the combination 65 of a three-way valve arranged in the fuel supply line, an operating finger piece at each end of the valve, a two-part housing for the valve, each part having a slot to receive a finger piece, a pair of spaced parallel legs carried by each part and having aligned openings near the ends, each part 70 having openings to receive the legs of the other part, locks arranged to connect each pair of legs upon the outside of the housing, and ribs formed upon the inner faces of the housing parts to snugly engage the valve body at the juncture of the several branches.

In testimony whereof, I affix my signature.

WILLIAM F. LEVISON.
